UNITED STATES PATENT OFFICE.

MOSES F. PATTON, OF TUSCALOOSA, ALABAMA, ASSIGNOR TO A. SCHRAEDER'S SON, INCORPORATED, OF BROOKLYN, NEW YORK, A CORPORATION OF NEW YORK.

DUST-CAP FOR VALVE-STEMS.

1,358,649.

Specification of Letters Patent.

Patented Nov. 9, 1920.

Application filed February 26, 1915, Serial No. 10,773. Renewed June 14, 1917. Serial No. 174,791.

To all whom it may concern:

Be it known that I, MOSES F. PATTON, a citizen of the United States of America, residing at Tuscaloosa, in the county of Tuscaloosa and State of Alabama, have invented certain new and useful Improvements in Dust-Caps for Valve-Stems, of which the following is a specification.

My invention relates to an improvement 10 in dust caps for tire valve stems, and my object is to simplify and quicken the manner of attaching and detaching the cap from the stem without appreciably increasing the cap's cost over the present type of dust caps 15 and their attaching means.

According to my invention the dust cap has its lower end slotted and provided internally with threads to form a split nut. The split end of the cap is adapted to be received 20 in a sleeve which serves as a packing washer and has an internal wedge surface for contracting the threaded end portions of the cap to and forcing them together as a completed nut to mesh with the threads on 25 the valve stem and retain the cap in position.

A further object of my invention is to simplify the manner of holding the dust cap and sleeve assembled and to this end I 30 provide either a raised annular shoulder on the dust cap and a ring nut in the outer end of the sleeve to form a stop for the shoulder or I interlock the sleeve and dust cap by a stop pin and slot which permits of the necessary 35 relative movements longitudinally of the cap to contract or release the split nut from the valve stem, or I adapt some other suitable form of connection.

My invention further comprises the novel 40 details of construction and arrangements of parts which in their preferred embodiments only are hereinafter more particularly described and illustrated in the accompanying drawings which form a part of this specification, and in which:—

Figure 1 is a vertical sectional view through the cap and sleeve showing the cap released from the valve stem.

Fig. 2 is a similar view showing the cap 50 nut interlocked with the valve stem.

Fig. 3 shows the several parts juxtaposed and ready for assembling.

Fig. 4 is a view similar to Fig. 1 of a modification of my invention in which a pin and

elongated slot are substituted for the shoulder and nut. 55

Similar reference numerals refer to similar parts throughout the drawings.

The dust cap 1 is similar to the present style of dust caps, being formed as a thin 60 tubular metal body provided at an intermediate point with an annular bead or shoulder 2 and in its lower portion below the bead having a plurality of vertical slots 3 terminating at their upper ends in enlarged openings 4. Preferably there are four of these slots and openings punched in the inner end of the cap and they are arranged equi-distantly about the cap. There are thus formed a series of movable arms 70 which constitute longitudinal extension of the cap portions. These arms are preferably in normally expanded condition, so that they slide freely over the valve stem or casing. The outside edge 5 of the split end 75 of the cap is beveled at an incline toward the center line of the cap and internally of the split end of the cap I provide threads 6, preferably by threading this end of the cap before it is slotted so that these threaded 80 sections are adapted, when contracted, to meet and form a continuous nut. Both the slotted end and the shoulder 2 on the cap are adapted to be received in a sleeve member 7, the lower end of which is pressed or 85 drawn inwardly to form an annular contracted beveled or wedge surface 8 below which it is outturned sharply at 9 and formed to provide a seat for the ring packing 10. This end 9 and the packing 10 of 90 the sleeve are adapted to engage the wheel rim and take the place of the ordinary packing nut.

When the beveled face 5 of the slotted sections of the cap is forced downwardly 95 against the wedge face 8 of the sleeve, the nut sections are contracted into engagement with the threads on the valve stem 11. The upper end of the sleeve 7 is internally threaded at 12 and an annular nut 13 is externally threaded to engage the threads 12. The bore of the nut 13 is adapted to receive the cap 1 with a close sliding fit and it is preferably provided with an annular packing ring 14 in the bore which will prevent 105 moisture or dirt working inwardly along the cap 2 to sleeve 7. The nut 13 is provided with an upper beveled shoulder 15 which

is adapted to engage the top of the sleeve 7 and has opposite openings 16 to receive a spanner wrench.

In the construction shown in Fig. 4 the sleeve 7^a, corresponding to 7, is provided near its upper end with a set screw or stop pin 17 and above that with an annular groove 18 which receives a ring packing 19 adapted to project slightly into the bore of the sleeve. The cap 1^a is similar to 1 except that it has no shoulder 2 but instead is provided with a vertically elongated slot 20 adapted to receive the pin or set screw 17 and interlock the sleeve and cap while permitting them sufficient relative longitudinal movement to provide for the expanding or contracting of the split nut of the cap. The packing 18 will permit the dust cap to be passed through it but will prevent moisture and grit working in between the cap and the sleeve. In this arrangement the sleeve fits snugly about the cap.

It will be noted that the several parts can be very simply and cheaply manufactured of spun or drawn tubing and but a minimum number of parts are required to accomplish the purposes I have in view.

In practice, to apply the cap, the sleeve is passed freely over the valve stem and the cap is forced down until its nut is contracted into engagement with the threaded valve stem, whereupon the cap and sleeve are given a half turn which firmly interlocks the cap to the stem and presses the packing 10 against the wheel member. To remove the cap it is only necessary to give the cap a reverse half turn and lift the cap which will permit its nut to spread and release the valve stem when the cap and sleeve can be lifted freely from off the valve stem.

While I have shown and described one form of the invention, it will be understood that I do not wish to be limited thereto, since various changes may be made therein without departing from the spirit of the invention.

Having thus described my invention in its preferred embodiment and with the understanding that it may be variously modified within the scope of my invention, what I claim as new and desire to secure by Letters Patent, is:—

1. In combination, in a dust cap for valve stems, an integral tubular cap having its open end internally threaded and split longitudinally to make it collapsible, and a combined sleeve and washer formed of tubing deformed to present an internal annular beveled shoulder and a bottom washer seat, said sleeve being adapted to receive said cap and said shoulder to collapse its threaded split end into engagement with the valve stem, and retaining means comprising interlocking shoulders on cap and sleeve 65 adapted to hold the cap from disengagement

from the sleeve while leaving it free for limited longitudinal movement therein for the purposes described.

2. A cap for valve stems comprising, in combination, a sleeve surrounding the valve stem and forming a washer at its rim engaging end and having an internal contracted tapering portion, an integral dust cap having its open end longitudinally slotted and internally threaded, the threaded end of the dust cap being adapted by engagement with said wedging portion of the sleeve to be collapsed into engagement with the threads on the valve stem, and stop means to prevent the disengagement of the cap from the sleeve while leaving said parts free for limited relative longitudinal movements.

3. In a device of the character described, a dust cap having its open end longitudinally slotted and internally threaded, a sleeve adapted to receive the dust cap and having a wedging portion adapted to engage and collapse the slotted threaded end of the cap, detachable means to hold the cap and sleeve assembled while permitting limited relative longitudinal movements, and means to pack the joints between the cap and sleeve and between the sleeve and the wheel rim, substantially as described.

4. The combination of a tubular member constituting the body of the device and having formed as extensions thereof a series of spring arms, said spring arms being provided at their lower ends with screw-threads, and a foot portion surrounding said spring arms and having a shoulder adapted to move said spring arms inwardly when the foot portion is stationary and the tubular member is pressed toward it, and said foot member extending upwardly around said tubular member to a point beyond said spring arms.

5. A dust cap having spring arms and a foot portion adapted to engage a stationary part, and having means for compressing said arms, when said arms are pressed inwardly and a portion extending upwardly above said spring means to form a bearing face for the cap portion.

6. A dust cap having an elongated cap portion formed at its lower ends with a series of integral spring arms constituting extensions of said cap portion, and a foot portion encircling said cap portion and provided with a beveled portion against which said spring arms act, and said foot portion extending upwardly around said cap portion to a point adjacent to the inner ends of said spring arms.

7. The combination of a movable member adapted to fit over a screw-threaded part, said member having normally expanded movable arms formed as longitudinal extensions thereof, a stationary member with

relation to which the first is movable, and said second member having a part adapted to move said movable arms inwardly to engage said threaded part when the movable member is moved relatively to the stationary member.

8. The combination of a tubular member constituting the body of the device and having formed as longitudinal extensions thereof of a series of normally expanded spring arms, said spring arms being provided at their lower ends with screw-threads, and a foot portion surrounding said spring arms and having a shoulder adapted to move said spring arms inwardly when the foot portion is stationary and the tubular member is pressed toward it.

9. A dust cap having a cap portion, a series of normally expanded spring arms forming longitudinal extensions of said cap portion, said spring arms having threads at their lower ends, and a foot member having a shoulder adapted to force said threaded ends toward each other when the cap portion is pressed into the foot portion.

10. A dust cap having a cap portion, a series of normally expanded spring arms forming longitudinal extensions of said cap portion, said spring arms having threads at their lower ends, and a foot member having a shoulder adapted to force said threaded ends toward each other when the cap portion is pressed into the foot portion, said foot portion extending upwardly to a point beyond said spring arms.

11. A dust cap having a cap portion having formed integral therewith a series of normally expanded spring arms, said spring arms having threads adapted to engage a screw-threaded valve or the like, and a foot portion having a shoulder adapted to engage the ends of said spring arms to move them inwardly when said cap portion is pressed into the foot portion.

12. A dust cap having a cap portion having formed integral therewith a series of normally expanded spring arms, said spring arms having threads adapted to engage a screw-threaded valve or the like, and a foot portion having a shoulder adapted to engage the ends of said spring arms to move them inwardly when said cap portion is pressed into the foot portion, said foot portion extending upwardly and having a bearing against said cap portion at a point remote from the ends of said spring arms.

13. The combination of a movable member adapted to fit over a screw-threaded part, said member having normally expanded movable arms formed as longitudinal extensions thereof, a second member extending below the ends of said arms so as to contact with a fixed abutment, and said second member having a part adapted to move said movable arms inwardly to engage the threaded

part when the movable member is pressed toward said abutment.

14. The combination of a tubular member constituting the body of the device and having formed as longitudinal extensions thereof of a series of normally expanded spring arms, said spring arms being provided at their lower ends with screw threads, and a foot portion surrounding said spring arms and extending below the ends of said arms so as to adapt it for contact against a fixed abutment, and said foot portion having a shoulder adapted to move said spring arms inwardly when said tubular member is pressed toward said abutment.

15. A dust cap for tire valves, comprising a base or foot portion, a tubular casing having internally threaded parts adapted to be sprung into contact with the threaded portion of a tire valve, and a sleeve around said threaded parts of less height than said casing and forming a closure around said threaded parts, said base having means cooperating with said threaded parts to force them into contact with said threaded portion of a tire valve.

16. A dust cap for tire valves, comprising a base or foot portion, a tubular casing having internally threaded parts adapted to be sprung into contact with the threaded portion of a tire valve, and a sleeve around said threaded parts of less height than said casing and forming a closure around said threaded parts, said base having means cooperating with said threaded parts to force them into contact with said threaded portion of a tire valve, said sleeve being formed as an extension of said base portion.

17. A dust cap for tire valves, comprising a tubular casing having internally threaded parts adapted to be sprung into contact with the threaded portion of a tire valve, means for forcing said threaded parts into contact with said threaded portion of a tire valve, and a sleeve around said threaded parts, of less height than said casing and forming a closure around said threaded parts.

18. A dust cap for tire valves, comprising a tubular casing having a closed portion and having one end slitted to form arms, said arms being internally provided with threaded parts and adapted to be sprung into contact with the threaded portion of a tire valve, means for forcing the threaded parts of said arms into contact with said threaded portion of a tire valve, and a sleeve of less height than said casing and forming a closure around said slitted part of the casing.

In testimony whereof I affix my signature in presence of two witnesses.

MOSES F. PATTON.
